US00D842523S

(12) **United States Design Patent** (10) **Patent No.:** **US D842,523 S**
Mishan et al. (45) **Date of Patent:** **** Mar. 5, 2019**

(54) **ROCK DISK LIGHT**

(71) Applicant: **E. MISHAN & SONS, INC.**, New York, NY (US)
(72) Inventors: **Edward I Mishan**, New York, NY (US); **Fred Hollinger**, Monroe Township, NJ (US)

(73) Assignee: **E. Mishan & Sons, Inc.**, New York, NY (US)

(**) Term: **15 Years**

(21) Appl. No.: **29/662,170**

(22) Filed: **Sep. 4, 2018**

(51) LOC (11) Cl. **26-05**

(52) U.S. Cl.

USPC **D26/67**; D25/113

(57) **CLAIM**

The ornamental design for a rock disk light, as shown and described.

DESCRIPTION

FIG. 1 is a top left perspective view of a rock disk light showing our design therefor;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.

The broken lines define the bounds of the claimed design and form no part thereof.

1 Claim, 5 Drawing Sheets
